UNITED STATES PATENT OFFICE.

JASPER SPEESE, OF WEST MILTON, PENNSYLVANIA, ASSIGNOR TO THE SPEESE MANUFACTURING COMPANY, OF SUNBURY, PENNSYLVANIA, A CORPORATION OF PENNSYLVANIA.

FOUNTAIN-BRUSH.

1,127,817.

Specification of Letters Patent. Patented Feb. 9, 1915.

Application filed January 15, 1914. Serial No. 812,817.

To all whom it may concern:

Be it known that I, JASPER SPEESE, a citizen of the United States, residing at West Milton, in the county of Union, State of

5 Pennsylvania, have invented certain new and useful Improvements in Fountain-Brushes, of which the following is a description, reference being had to the accompanying drawings, forming a part hereof.

10 My invention relates to brushes of the type in which the bristles are clamped and held between an inner and outer member and the invention has for its object to provide a brush which shall be simple and in-

15 expensive in construction and will be adapted to be constructed with the least possible number of parts, and in which the parts shall be adapted to be made by cutting and bending by dies without the necessity for

20 machining or finishing, may be quickly assembled and will be firmly secured together without fastening means other than means formed integral with the members.

A further object is to provide a construction which will be particularly adapted to be used as a reservoir or fountain brush to supply a cleansing or other fluid to the bristles as required in use.

With these and other objects, hereinafter explained, in view my invention consists in the construction and combination of elements hereinafter described and particularly pointed out in the claims.

Referring to the drawings: Figure 1 is a 25 side elevation of a complete brush embodying my invention. Fig. 2 is a longitudinal sectional view on line 2—2 of Fig. 3, the bristles being partly broken away. Fig. 3 is a cross sectional view on line 3—3 of Fig. 1; Figs. 4, 5 and 6 are respectively a plan, end and edge view of the blank from which the inner member of the brush is formed. Figs. 7, 8 and 9 are respectively a plan, end and edge view of the blank 30 shown in Figs. 4, 5 and 6 after it has been subjected to the punching operation by which the teeth are formed. Figs. 10 and 11 are respectively a plan and end view of the blank after it has been subjected to a further operation to form the spacing projections. Fig. 12 is a view of the blank 35 shown in Fig. 10 partly in edge and partly on line 12—12. Fig. 13 is a cross sectional view on line 13—13 of Fig. 10. Figs. 14,

15 and 16 are respectively a bottom plan 55 view, an end view and a side view of blank from which the inner member is formed after it has been partly bent to form. Fig. 17 is a cross sectional view on line 17—17 of Fig. 14. Figs. 18, 19 and 20 are respectively a bottom plan view and end view and a side elevation of the inner member bent to its complete form. Fig. 21 is a cross sectional view on line 21—21 of Fig. 18 and Fig. 22 is a plan view of the inner and outer 60 members assembled, the bristles being omitted.

In the drawings 1 indicates the outer or inclosing member of the brush, 2 indicates the inner or trough member and 3 indicates 70 the bristles which are held between the inner and outer members.

4 indicates a wick carried by the trough member and serving to retain and distribute the fluid by which the brush is moistened. 75

The outer or inclosing member 1 is curved in cross section to substantially semicircular or inverted U form for the main portion of its length as shown in Fig. 3 with reduced portions 5 at its ends and has at its mid 80 length a flattened portion 6 having a circular opening 7 therein to receive the end of a handle (not shown). The outer member is preferably strengthened by transverse raised ribs or corrugations 8, and it is provided on 85 each of its depending sides with inwardly projecting tongues 9 formed by cutting and bending.

The inner or trough member 2 is formed of a strip of sheet metal which is first cut 90 or punched to the form shown in Figs. 4, 5 and 6, the body of the blank having parallel edges as shown, the edges terminating at their ends in tongues 10 and 11. Midway between these tongues 10 and 11 is a central 95 tongue 12 which is itself provided with terminal oppositely extending relatively short fingers 13, 14 and intermediate relatively long oppositely extending tongues 15, 16. After this blank is cut or punched to the 100 shape shown in Fig. 4 a series of tongues 17 are formed near each edge by cutting and bending as indicated in Figs. 7, 8, and 9. By a further operation a series of small teats 18 are formed in the body of the blank, 105 these teats being raised from the surface from which the tongues 17 extend, and similar teats 19, 20 are formed near the tongues

10 and 11 but projecting from the surface opposite to that from which the tongues 17 project. At the same time projections 21, 22 midway between the ends of the blank are 5 formed. These also extend from the surface of the blank opposite to that from which the tongues 17 project. At the same time that these results are produced the tongues 10 and 11 are bent at right angles to the body 10 of the blank so as to project in the same direction as the tongues 17, and the tongues 13, 14 are bent at right angles to the body of the tongue 12, but in a direction opposite to the direction in which the tongues 17 project. 15 The blank will then appear as shown in Figs. 10, 11, 12 and 13. The blank is then ready to be bent into shape. This is effected by two operations, the result of the first of which is shown in Figs. 14, 15, 16 and 17. 20 By this operation the portion of the body of the blank is bent longitudinally into a U form in cross section and the side portions carrying the tongues 17 are bent toward the apex of the U, the device as thus bent presenting the appearance in cross section of an inverted W as shown in Figs. 15 and 17, the 25 tongues 17 and the terminal tongues 10 and 11 extending outward, the tongues 15, 16 extending upward parallel with the sides of the U or trough, the tongues 13, 14 extending outward at about right angles to the sides of the U or trough, the teats 18 extending inward within the U or trough and the teats 19, 20 extending inward from the side 30 portions. The wick 4 is then placed in the U or trough and the side portions are bent inward and the side of the U or trough pressed inward so that the teats 18 project slightly into the material of the wick so as 35 to hold it firmly in place and yet not to so far compress it as to prevent it from absorbing the cleansing fluid. At the same time the tongues 15, 16 are pressed into the end portions of the wick so as to compress it 40 and check any excess of flow of the cleansing fluid. The parts are now ready to assemble. A suitable mass or mat of bristles is bent over the inner member as shown in Fig. 3 and the inner member with its bristles 45 is inserted into the outer member and the sides of the outer member are pressed together so as to cause the ends of the tongues 9 to enter the openings left in the side portions of the inner member in the process of 50 forming the tongues 17, the tongues 9 being somewhat longer than the tongues 17. The end tongues 10, 11 bear at their outer end against the inside of the outer member thus spacing the inner and outer members apart. 55 The ends of the tongues 13, 14 fit within the reduced ends of the outer member and serve to hold the ends of the mass of bristles against undue spreading outward. The projections 21, 22 when the parts are assembled 60 come directly below the opening 7 forming

an enlarged opening between the walls of the trough to receive the cleansing fluid supplied through the opening 7.

It will be understood that in the operation of the brush the cleansing fluid supplied through the opening 7 will be absorbed by the wick and will be supplied to the bristles by capillary attraction. The tongues 17 and 9 serve to separate the bristles into sections and aid in the distribution of the cleansing fluid, the tongues 9 also serving as the locking means for securing the two members together.

The teats 19, 20 are formed of sufficient depth to bear against the walls of the trough when the inner member is completed, thus serving as spacing means and with the tongues 10, 11 aid in forming a rigid structure when the members are finally assembled.

The material of which the outer member is formed is preferably heavier than that from which the inner member is formed.

It will, of course, be understood that the term "bristles" is intended to include all fibrous material suitable for or used in brushes. It will be further understood that while the brush shown and described is particularly adapted and intended to be used as a fountain brush it may be used as a dry brush. It will further be understood that I do not desire to be restricted to the precise features of construction shown and described as it is obvious that the details of construction may be considerably varied without departing from the spirit of the invention.

Having thus described my invention what I claim is:

1. A brush in which the bristles are held between an inner and an outer member, means for securing the two members together consisting of tongues integrally formed with one member and openings in the other member adapted to be engaged by said tongues.

2. A brush in which the bristles are held between an inner and an outer member U shaped in cross section, means for securing the two members together, consisting of inwardly projecting tongues formed integrally with the outer member and openings formed in the inner member adapted to be engaged by the tongues of the outer member.

3. In a brush in which the bristles are held between an inner and an outer member, an inner member provided on its outer sides with outwardly projecting tongues formed integrally therewith by cutting and bending and an outer member provided on its inner sides with inwardly projecting tongues adapted to enter and engage the openings in the sides of the inner member from which the first named tongues were cut.

4. In a brush in which the bristles are held between an inner and an outer member, an inner member provided on its outer sides with outwardly projecting tongues 5 formed integrally therewith by cutting and bending and adapted to extend into the mass of bristles, an outer member provided on its inner sides with inwardly projecting tongues adapted to engage the openings in 10 the sides of the inner member from which the tongues were cut, and spacing tongues carried by the inner member adapted to bear at their ends against the inner sides of the outer member.
- 15 5. In a brush in which the bristles are held between an inner and an outer member, an inner trough shaped member having depending sides provided with outwardly projecting tongues formed integrally therewith by cutting and bending 20 and an outer member U shaped in cross section provided on its inner sides with inwardly projecting tongues formed integrally therewith adapted to engage the 25 openings in the sides of the inner member from which the tongues were cut.
6. In a brush in which the bristles are held between an inner and an outer member, an inner member formed from a single 30 strip of sheet metal bent to form a central trough adapted to receive a wick and provided on the interior surfaces of the trough with teats adapted to engage and hold the wick.
7. In a brush in which the bristles are held between an inner and an outer member, an inner member formed from a single strip of sheet metal bent to form a central trough adapted to receive a wick and provided on the interior surfaces of the trough 40 with teats adapted to engage and hold the wick, and tongues at the ends of the trough adapted to be compressed against the wick.
8. In a brush in which the bristles are held between an inner and an outer member, an inner member formed from a single strip of sheet metal bent to form a central trough adapted to receive a wick and having at each end a central tongue provided with a pair of tongues adapted to be compressed against the wick.
9. In a brush in which the bristles are held between an inner and an outer member, an inner member formed from a single strip of sheet metal bent to form a central 55 trough adapted to receive a wick and having at each end a central tongue provided with a pair of tongues adapted to be compressed against the wick, and also having at its outer end a pair of horizontally extending tongues.

This specification signed and witnessed this sixth (6") day of June, A. D. 1913.

JASPER SPEESE.
